CLOTHES HANGER FOR AUTOMOBILES OR THE LIKE

Harry Bookman and Elof E. Dalton, Los Angeles,
Calif.; said Dalton assignor to said Bookman

Application September 29, 1950, Serial No. 12,402

Term of patent 14 years

(Cl. D14—6)

To all whom it may concern:

Be it known that we, Harry Bookman and Elof E. Dalton, both citizens of the United States, residing in Los Angeles, county of Los Angeles, State of California, have invented a new, original, and ornamental Design for Clothes Hanger for Automobiles or the like, of which the following is a specification, reference being had to the accompanying drawing, forming part thereof.

Figure 1 is a perspective view of a clothes hanger for automobiles or the like, showing our novel design;

Figure 2 is a similar view showing the same open for use;

Figure 3 is a front view;

Figure 4 is a side view.

The rear of the hanger is plain.

We claim:

The ornamental design for a clothes hanger for automobiles or the like, substantially as shown and described.

HARRY BOOKMAN.
ELOF E. DALTON.
